UNITED STATES PATENT OFFICE.

JOHN ECKERT GREENAWALT, OF DENVER, COLORADO.

PROCESS OF SUBJECTING MATERIALS TO THE ACTION OF AIR OR OTHER GASES.

No. 921,645.

Specification of Letters Patent.

Patented May 11, 1909.

Original application filed December 27, 1901, Serial No. 87,510. Divided and this application filed January 26, 1904.
Serial No. 190,726.

To all whom it may concern:

Be it known that I, JOHN E. GREENAWALT, a citizen of the United States of America, residing in the city and county of Denver and State of Colorado, have invented certain new and useful Improvements in Processes of Subjecting Materials to the Action of Air or other Gases; and I do declare the following to be a full, clear, and exact description of the invention, such as will enable others skilled in the art to which it appertains to make and use the same, reference being had to the accompanying drawings, and to the figures of reference marked thereon, which form a part 15 of this specification.

My invention relates generally to a process of treating materials by subjecting them to the action of gas and more specifically to an oxidizing process in which air or other 20 gases are advantageously introduced to the materials by forcing the air or gas or both from below up through a porous hearth or bed directly into the material lying on the bed or hearth above.

In this specification my process will be described as applied to the oxidation or roasting of ores in order to free the ore from those elements which render it refractory and prevent their successful and economical 30 treatment when in the raw or natural state in which they are taken from the mines.

My object is to eliminate the mechanical and metallurgical difficulties encountered in the preparation of gold, silver and copper 35 ores for the extraction of the values by a chemical solution.

This application is divided out of an application filed by me Dec. 27th, 1901, Serial No. 87,510, entitled improvements in roasting furnaces which last named application was divided out of an application filed by me Oct. 12th, 1901, Serial No. 78,481.

The roasting operation forms a very important factor in the successful extraction of the 45 precious metals from their ores by means of a chemical solution; the object sought being to leave the precious metals in a condition to be acted upon by the solvent and to put the baser metals and elements in a condition to resist the action of the solvent. To do this properly requires an abundant supply of oxygen in order to thoroughly oxidize all the oxidiz-

able elements before subjecting the ore to the high temperature required by some of the base elements to resist the gold dissolving 55 solution.

The principal difficulties encountered in the oxidizing of ores as heretofore practiced are encountered in connection with the air supply. In the roasting processes as heretofore practiced in reverberatory furnaces, except in connection with the furnaces built under my supervision for the carrying out of the process herein set forth, the only means of supplying air is at the upper surface of the 60 ore and this is so slow and imperfect that the ore is generally moved into the highly heated region of the furnace before all the combustible elements have been oxidized; the result is that some of the mineral particles become 65 cindered and fused, thus preventing a high percentage of extraction of the gold and silver. I have determined that all of the combustible elements of the ore can be burned or oxidized at a comparatively low 70 temperature when the ore is supplied with an abundance of pure air, and that the oxidized mineral particles are left open and porous; also, that the capacity of the furnace 75 is largely increased.

The invention will now be described in detail reference being made to the accompanying drawing which illustrates a suitable apparatus for carrying out or practicing my invention.

Figure 1 represents a cross section of the furnace. Fig. 2 is a section taken lengthwise of the furnace, the parts being shown on a smaller scale. Fig. 3 shows an important modification of the apparatus.

In Fig. 1 of the drawing is shown the method of introducing the air to the ore through the porous hearth, also the manner of cooling the rabble tracks. In the construction of this furnace I prefer to build a solid hearth for the furnace and construct this hearth of concrete with a layer of strong cement for a finished coating, leaving a space of about nine inches between this hearth proper and the lowest point of the 95 rabble plows. This space, which extends almost the entire length of the furnace, I divide into sections approximately square by solid walls reaching nearly to the lowest 100

point of the rabbles; the object of this wall being to prevent the air introduced into one section from escaping into the adjoining section. The dividing of this space between the hearth and the rabble plows into sections is necessary to control the amount of air delivered to the ore at the various stages of the roasting operation. At the side of the furnace I arrange a large conduit 5 leading to the center of each section. The object of this conduit is to make the interior of the furnace accessible for repairs, etc. In the space between the hearth and the rabbles I build what I prefer to call a porous filter 8 consisting of large pieces of ore at the bottom and in the conduit, with smaller pieces above them and so on until the last four inches which consists of ore as fine as that which is to be roasted and from which the intensely fine dust has been screened. Upon this filter the ore rests in its passage through the furnace, the rabbles passing over the filter and moving the ore ahead at regular intervals. The air and steam, when it is desirable to use steam in the roasting operation are passed under pressure from the main pipes 9 and 17 to a branch pipe 10 into the conduit 5 of each section and thence to the hearth. The large spaces among the coarse ore, permit the air to quickly and evenly distribute itself over the hearth and then filter or percolate uniformly through the interstices between the fine ore particles; the idea being not to create a blast of air, but to simply have a light pressure and force the air through the pores of the filter without disturbing the porous filter or the ore particles. The action is analogous to water percolating through ore placed on a sand filter. This construction can also be used to introduce chlorin or other gaseous products into the ore mass during its passage through the furnace. While I prefer ore for the construction of this filter, it is evident that any suitable fine porous material, such as fine sand, mineral wool, fibrous asbestos, etc., supporting the weight of the ore in its passage through the furnace, with means to conduct air through it into the ore mass, would answer the purpose. However, low grade ore similar to that regularly treated is far preferable, since it is easy to get and place into position and in case any of the precious metals find their way into the filter, it can be removed and given the regular treatment for the extraction of whatever values it may contain.

The tracks 14 upon which the truck wheels 13 of the rabbles run, are made of hollow cast iron, the interior of which is sealed from the furnace, and arranged for cooling either by air or water, preferably by water indirectly by placing a pipe 15 filled with water into it. This water pipe will

keep the casting sufficiently cool to maintain its original position and condition. The hollow cast iron track also has a flange 14^a to receive the tile partition 16 separating the ore from the track, so that the tile can be bolted to the track, so that it will always retain its position relatively to the track.

In Fig. 2 are shown the sprocket-wheels 21 and 27 over which the chains and rabbles travel, and also the track 22 above the furnace where the rabbles and chains are cooled on their return journey. This section also shows the porous hearth and the walls 23 dividing the porous hearth into sections, so that varying quantities of the air can be delivered to the ore mass during its travel through the furnace.

The feeding of the ore to the furnace hearth I accomplish as follows: In the ore bin 24, I place an adjustable gate 25 which can be raised or lowered, thus raising or lowering the surface of the ore mass as it comes from the bin. The ore in the bin being fine and perfectly dry always assumes approximately the same angle, and by raising or lowering the gates, the rabbles cut into the ore to a greater or less extent and consequently the amount of ore fed into the furnace can be varied as desired. The shaft 26 carrying the rear sprocket wheels 27 is mounted on adjustable take-up boxes the adjustment being effected by screws 28. The chains used ordinarily for this purpose are quite heavy and there is considerable sag in the chain between the rabbles, so that the shaft 26 can be moved backward or forward considerably without interfering with the operation of the chain or rabbles; consequently by means of the screws 28 the rabbles can be made to cut into the ore to a greater or less extent and the amount of ore fed into the furnace governed accordingly.

I prefer to heat the furnace with producer gas which I introduce at 29 (see Fig. 2) permitting it to flow over the hot roasted ore before it is withdrawn from the pit or hopper 30. It passes through the opening 31 into the furnace.

Fig. 3 shows a track 14^c constructed with its interior exposed to the atmosphere so that it is accessible from the outside. It also shows the manner of constructing the porous hearth for hand furnaces where hoes or hand rakes are used to stir the ore. In this case there is a space of about one inch left between the bricks of the hearth and this space is filled with porous material and supplied with air. While the introduction of the brick diminishes the porous area considerably, yet it is necessary in order to protect the porous material from the hoe or rake of the workmen in hand furnaces.

Having thus described my invention, what I claim is:

1. The process of oxidizing ore, which consists in placing the ore on a bed composed of a substance which is naturally porous, subjecting the ore to heat, and then forcing air upwardly through the bed and into the ore.
2. The process of roasting ore sulfids, which consists in placing the sulfids on a porous bed of loose granular material, and

then subjecting the sulfids to heat and forcing air upwardly through the bed. 10

In testimony whereof I affix my signature in presence of two witnesses.

JOHN ECKERT GREENAWALT.
